(57) **CLAIM**

The ornamental design for a portion of a front panel for an electronic device, as shown and described.

DESCRIPTION

FIG. 1 is a perspective view, from the front and above, of a first embodiment of a portion of a front panel for an electronic device showing my new design.

FIG. 2 is a front view thereof; and,

FIG. 3 is a perspective view, from the front and above, of a second embodiment my design, which differs from the first embodiment in that the lens and the four elongated light pipes are translucent.

The broken lines shown in FIGS. 1-3 represent environmental subject matter and form no part of the claimed design. The rear, top, bottom, left side and right side views are omitted and form no part of the claimed design.
